UNITED STATES PATENT OFFICE.

EDWIN C. LAIRD, OF RICHMOND, VIRGINIA.

BEDCLOTHES HOLDER.

Application filed August 7, 1923. Serial No. 656,222.

To all whom it may concern:

Be it known that I, EDWIN C. LAIRD, a citizen of the United States, residing at Richmond, in the county of Henrico and

5 State of Virginia, have invented certain new and useful Improvements in Bedclothes Holders, of which the following is a specification.

This invention relates to bed covering 10 holders and is especially designed to provide a safety holder serving to securely and properly retain the bed covering over children, and prevent their exposure to cold drafts as long as they remain lying in the 15 bed.

The main object of the invention is to provide simple, economical, durable and effective bed clothes holders adapted to securely retain the bed clothing in its proper position 20 over the bed, and secure said clothing in such position during the occupancy of the bed.

Another object of this invention is to so construct my novel bed clothes holders that 25 when attached to the bed posts they will readily yield to sudden movements of the covering, such as are caused by the turning, twisting or kicking movements of the occupants of the bed, yet at the same time 30 safely and securely maintain the covering in its arranged position over the bed.

Further objects of the invention are to provide means for retaining bed clothing over the bed which are so shaped that they 35 will hold either a small or a large roll of covering; that the further the roll of bed clothes are drawn within the holder, the tighter the hold becomes; that are formed of a plate of flat metal without any seams 40 or rough places to contact with the bed clothing and thereby tear, wear, or have a tendency to injure the clothes, said plate being formed with a central divergent and convergent opening therethrough forming a 45 series of scalloped or corrugated inner convergent jaws for securely retaining a roll of bed clothes therebetween.

The foregoing and such other objects as 50 may appear from the ensuing description are accomplished by the construction, arrangement, combination and location of the parts hereinafter more fully described, illustrated in the accompanying drawings, and particularly set forth in the claims appended 55 hereto, it being understood that slight changes in the precise form, proportions and

minor details of the construction may be resorted to without departing from the spirit or sacrificing any of the advantages 60 of the invention.

In the accompanying drawings forming a part of this specification it will be seen that:

Figure 1 is a perspective view showing the improved bed clothes holder embodying 65 my invention secured to the upright posts of a bedstead.

Figure 2 is an enlarged plan of one of the bed clothes holders detached from the bed clothes and bedstead, and showing the 70 bedstead securing means broken away, and

Figure 3 is a view partly in side elevation and partly in section showing the bed clothes holder removed from the bed. 75

In the embodiment of my invention as illustrated, it will be seen by reference to Fig. 1, that the numeral 2 designates the head posts of an ordinary bedstead, 3 the foot posts thereof, 4 a side rail connecting the head and foot portions, and 5 the bed clothing properly arranged to cover the 80 bed and its occupants.

Encircling the head and foot posts, at each side of the bed, is a loop or band 6 composed preferably of an elastic fabric or webbing, the inner end of which is passed through an elongated slot 7 formed through the outer end portion of the metallic bed clothes holder 8, and is fixedly secured to said holder by a line of stitching 9, said 85 loop or band being provided with a buckle 10 to permit each band to be so adjusted as to be properly secured and retained to its respective bed post of any size and dimensions. 90

Each bed clothes holder 8 is preferably formed from a plate of suitable metal, although it may be formed of suitable hard wood or other desirable material possessing the required strength and durability. The 100 said plate is formed with a central opening therethrough which opening is of sufficient dimensions to receive the bed clothing, the inner edges of said opening being divergent from the point 11 outwardly, while the remaining portion of the inner edges constituting the jaws 12, of the holder are gradually convergent to the inner terminal end of the opening. 105

It will be perceived that the inner edges 110 of the jaws 12 of the holder are scalloped or corrugated, so that where one jaw bulges

or forms a convex surface the opposite jaw at the corresponding position forms a concave surface, and at the same time the two jaws are converging which construction tends to materially increase the friction between the bed clothes and the jaws of the holder, hence it is obvious that by this improved arrangement additional friction is obtained from the protruding points of the scalloped or corrugated jaws, since when the bed covering has been forced into and between the scalloped jaws, there is not only friction from a downward pull of the covers, but there is also friction from a back pull of the covers, for when the covers are being released from the jaws they are compelled to follow the irregular, in-and-out contour of the opening between the jaws thus creating a decided additional friction.

It is evident that where the jaws of the holder have a straight edge it is possible for the occupant of the bed, when raising the covers to turn over, to so place the hand under the holder as to have the effect of releasing the clothes from the holder, but with the scalloped jaws this is not possible because there is both down friction and back friction.

It will be seen that this improved holder is so constructed that the inner edges thereof form rigid jaws, and is so shaped as to properly and securely retain a small or large roll of covering; that it will receive and retain the bed clothes after being arranged in the shape of a roll and thus retain the sheet adjacent to the face of the sleeper at all times; that the jaws are formed both scalloped and convergent so that the further the roll of clothing is drawn into and between the jaws the tighter the hold thereon becomes, and that the curved and smooth formation thereof prevents all tendency to damage the bed clothing, while at the same time the elastic fabric or webbing secured thereto yieldingly and resiliently insures each holder to retain the covering in its

proper and safe position over the bed regardless of the fidgety movements of the occupants of the bed.

It will be readily obvious that my improved and safety bed clothes holder is not only simple and thoroughly efficient for the purposes herein set forth, but that the number of parts employed have been reduced to a minimum.

Having thus described my invention what I claim and desire to secure by Letters Patent is:—

1. As a new article of manufacture, a bed clothes holder of the character described, comprising a metal plate formed with a central opening therethrough of sufficient dimensions for the reception of a roll of bed clothes within said opening, the inner upper edges of the opening being diverging, and its lower inner edges converging to the lower end of the opening and formed with a plurality of scalloped jaws having opposite concave and convex inner edges, and an elongated slot formed through one end of said plate for the reception of a resilient band adapted to yieldingly secure said holder to the post of a bedstead.

2. As a new article of manufacture, a bed clothes holder of the character described, comprising a flat metal plate formed with a central opening therethrough of sufficient dimensions for the reception of a roll of bed clothes within said opening, the inner upper edges of the opening being diverging, and its lower inner edges converging to the lower terminal end of the opening and formed with a series of corrugated jaws having oppositely disposed concave and convex inner edges, an elongated slot formed through one end of said plate for the reception of a resilient band, said band being secured thereto by a line of stitching, and means for adjustably and detachably securing said band to a bed post of any dimensions.

EDWIN C. LAIRD.
